HYDROFLUORIC ACID ALKYLATION PROCESS

Filed Aug. 10, 1943

UNITED STATES PATENT OFFICE

2,450,038

HYDROFLUORIC ACID ALKYLATION
PROCESSFrederick E. Frey, Bartlesville, Okla., assignor to
Phillips Petroleum Company, a corporation of
Delaware

Application August 10, 1943, Serial No. 498,117

13 Claims. (Cl. 260—683.4)

1 This invention relates to the treatment of organic compounds. More particularly, it relates to hydrofluoric acid alkylation of paraffins. This application is a continuation-in-part of my co-pending application, Serial No. 398,361 filed June 16, 1941, now Patent 2,347,945, issued May 2, 1944.

Hydrocarbon effluents from processes catalyzed by hydrofluoric acid contain small but important proportions of organic fluorine compounds. These compounds are undesirable because they decompose at elevated temperatures in subsequent treating steps to form hydrofluoric acid, which is corrosive, and because they represent an undesirable consumption of the catalyst. Furthermore, in the hydrofluoric acid alkylation of isoparaffins, the feed usually contains normal paraffins, which must eventually be separated from the alkylation effluent and must be removed from the alkylation system. Utilization of such normal paraffins other than as diluents in connection with the alkylation of isoparaffins is desirable.

An object of this invention is to improve hydrofluoric acid alkylation of paraffins.

A further object of my invention is to alkylate organic compounds.

Another object of this invention is to reduce catalyst consumption in alkylations of organic compounds catalyzed by hydrogen fluoride.

Other objects and advantages will be apparent from the accompanying disclosure and discussion.

In accordance with one specific embodiment of the present invention, an isoparaffin is alkylated with an olefin in the presence of hydrofluoric acid; the reaction mixture is separated into two liquid phases; the hydrocarbon phase is freed from hydrofluoric acid by azeotropic distillation; the acid-free hydrocarbon phase is fractionated into an unreacted-isoparaffin fraction, a normal-paraffin fraction, and an alkylate fraction; the isoparaffin fraction, together with its content of organic fluorine compounds, is recycled to the alkylation step; the other two fractions, together or separately, are defluorinated by contact with a suitable solid material and are withdrawn from the process. The normal-paraffin fraction is preferably dehydrogenated to furnish olefins for the alkylation step. Novel features of this invention can also be applied to the alkylations of other organic compounds with olefins, such as normal paraffins, cycloparaffins, aromatic hydrocarbons, and alkylatable, non-hydrocarbon de-

rivatives of such hydrocarbons, such as phenols, acids, ethers, etc.

An understanding of a preferred embodiment of this invention may be facilitated by reference to the accompanying exemplifying drawing, which is a schematic flow-diagram of one specific arrangement of equipment for practicing the invention.

A hydrocarbon alkylation feed enters alkylator 10 through inlet 11 controlled by valve 12. It comprises an alkylatable hydrocarbon, usually a low-boiling isoparaffin such as isobutane or isopentane, an alkylant, usually one or more olefins of three to five carbon atoms per molecule, such as the butylenes, and relatively inert diluent materials, such as normal butane and some propane. Concentrated, or substantially anhydrous, hydrofluoric acid enters alkylator 10 through inlet 13 controlled by valve 14 and is intimately mixed with the hydrocarbon feed by any suitable agitation means. The over-all mol ratio of isoparaffin to olefin is preferably as high as is economically feasible; it is usually from 4:1 to 20:1, but may be as high as 100:1 if desired. The volume ratio of acid to hydrocarbon is ordinarily between 0.5:1 and 2.0:1, but higher or lower ratios may be maintained if desired. The temperature in alkylator 10 is usually in the range of 75 to 150° F. although the reaction may be conducted at higher or lower temperatures. The pressure is sufficient to maintain all reactants in the liquid phase, but need not be unusually high. The time of residence of the reaction mixture in alkylator 10 is usually from 1 to 30 minutes; preferably it is from 5 to 15 minutes.

The reaction mixture is passed from alkylator 10 through conduit 15 and valve 16 to settler 20, in which the mixture is separated into two liquid phases by settling and/or centrifugation, aided if desired, by cooling. The heavier or hydrofluoric acid phase may be recycled directly to alkylator 10, as through conduit 21 controlled by valve 22; usually at least a part of the acid phase is passed through conduit 23 controlled by valve 24 to purification means, not shown, for purification before being recycled to alkylator 10.

The lighter or hydrocarbon phase is passed through conduit 25 controlled by valve 26 to azeotrope column 30, in which it is separated by fractional distillation into two fractions. The overhead fraction consists of a low-boiling, or azeotropic, mixture of hydrofluoric acid and propane and/or isobutane. This fraction is passed through conduit 31 controlled by valve 32, through con-

denser 33, and through conduit 34 to accumulator 35, in which the fraction is separated by gravity into two liquid phases. The heavier phase, which comprises substantially anhydrous hydrofluoric acid, is recycled through conduit 36 controlled by valve 37 to alkylator 10. The lighter or hydrocarbon phase is returned as reflux to azeotrope column 30 through conduit 38 controlled by valve 39. The kettle fraction from column 30, which comprises a substantially hydrogen fluoride-free hydrocarbon mixture and a minor proportion of organic fluorine compounds, chiefly alkyl fluorides, is passed through conduit 41 controlled by valve 42 to deisobutanizer 40. From deisobutanizer 40 an overhead fraction composed chiefly of isobutane, propane, and a minor proportion of organic fluorine compounds is passed through conduit 43 controlled by valve 44 to depropanizer 50. From the depropanizer, an overhead fraction comprising chiefly propane is withdrawn through outlet 51 controlled by valve 52, and a kettle fraction comprising chiefly isobutane and a minor proportion of organic fluorine compounds is recycled through conduit 53 controlled by valve 54 to alkylator 10. The organic fluorine compounds accompanying the isobutane thus become available for alkylating isobutane in alkylator 10. Of course, if a negligible or small amount of propane is present in the overhead of the deisobutanizer 40, all or a substantial portion of this may be returned directly to alkylator 10 by bypassing depropanizer 50, by means not shown. By this means, a large part or all of any hydrogen fluoride formed by decomposition reactions in deisobutanizer 40 will be directly returned to alkylator 10 also.

The kettle fraction from deisobutanizer 40 is passed through conduit 45 controlled by valve 46 to debutanizer 60, from which an overhead fraction comprising chiefly normal butane and a minor proportion of organic fluorine compounds is passed through conduit 61 controlled by valve 62 to defluorinator 90. This defluorinator may be any suitable closed chamber containing a contact material, such as aluminum oxide, bauxite, chromium oxide, zirconia, calcium oxide, magnesium oxide, or other solid, porous metal oxide catalytically active for hydrogenation and dehydrogenation reactions, or finely divided nickel, iron, or cobalt on a supporting material, that is capable of removing the organic fluorine at temperatures in the range of approximately 150 to 550° F., as more disclosed in my hereinbefore mentioned copending application Serial No. 398,361 (Patent 2,347,945). The material undergoing defluorination may be in either the vapor or the liquid phase; in the present instance liquid-phase treatment is preferable. A generally suitable space velocity is 1 to 2 liquid volumes per hour.

The substantially fluorine-free effluent from defluorinator 90 is passed through conduit 91 controlled by valve 92 to dehydrogenation means 100, which comprises any suitable means for catalytic and/or noncatalytic dehydrogenation. In such apparatus the temperature is usually from 800 to 1300° F. and the pressure is preferably less than 200 p. s. i.

The effluent from dehydrogenation means 100 is passed through conduit 101 controlled by valve 102 to fractionation means 110 which usually comprises two or more fractionating columns. In fractionation means 110 the hydrogenation effluent is separated into fractions, such as the following: (1) a fraction, comprising hydrogen and

hydrocarbons having less than three carbon atoms per molecule, that is withdrawn through outlet 111 controlled by valve 112; (2) an olefinic fraction, comprising chiefly butenes, propene, and unreacted butane, that is passed through conduit 115 controlled by valve 116 to alkylator 10; and (3) a kettle fraction, comprising hydrocarbons having more than four carbon atoms per molecule, that is removed from the system as through conduit 113 controlled by valve 114.

The kettle fraction from debutanizer 60 is passed through conduit 63 controlled by valve 64 to defluorinator 70, which is similar in construction and operating conditions to defluorinator 90, except that the temperature is preferably higher, in the range of 150 to 550° F. The contact material is preferably, although not necessarily, identical with that in defluorinator 90.

The substantially fluorine-free effluent from defluorinator 70 is passed through conduit 71 controlled by valve 72 to alkylate rerun column 80. An overhead light alkylate fraction, comprising hydrocarbons boiling in the motor-fuel range, is withdrawn through conduit 81 controlled by valve 82. A minor heavy alkylate fraction, comprising hydrocarbons boiling above the motor-fuel range, is withdrawn as a kettle product through conduit 83 controlled by valve 84.

It is to be understood that the drawing is merely diagrammatic; any additional equipment, such as condensers, pumps, heat exchangers, etc., necessary for practicing the invention in any particular installation may be supplied by anyone skilled in the art.

Further understanding of the invention may be aided by the following example:

Example

In a continuous hydrofluoric acid alkylation system an over-all hydrocarbon feed approximating 47 weight per cent normal butane, 40 weight per cent isobutane, 5 weight per cent propane, and 8 weight per cent butenes is contacted with anhydrous hydrofluoric acid, at a temperature of about 100° F., a gage pressure of 150 p. s. i., and a volume ratio of acid to hydrocarbon of 1:1, for a contact time of 10 minutes. The effluent mixture is passed to a settler in which the hydrocarbon phase is separated from the acid phase. The hydrocarbon phase is freed from dissolved hydrogen fluoride by distillation in an azeotrope column, and then it is distilled into several fractions in a series of fractionating columns. Propane is withdrawn from the system. Isobutane is recycled to the alkylation step; it contains alkyl fluorides corresponding to approximately 0.0300 weight per cent organically combined fluorine which is thus returned to the alkylation step for utilization of the alkyl fluorides as alkylating agent and simultaneous liberation of the organic fluorine as hydrofluoric acid. The normal butane is defluorinated by contacting with dehydrated bauxite at 180° F. and a space velocity of 2 volumes of liquid hydrocarbon per volume of bauxite per hour. The defluorinated normal butane fraction is dehydrogenated by a chromium oxide catalyst at a temperature of 1150° F. and a pressure of 150 p. s. i. The dehydrogenation apparatus is operated in such a manner that the effluent therefrom contains approximately 20 volume per cent olefins, mostly butenes. The dehydrogenation effluent is passed to a fractionating system, in which light gases are removed from the butenes, the propene, and the unreacted bu-

5

tane. These hydrocarbons are then recycled to the alkylation step, to become a part of the above over-all feed. A fraction of motor-fuel hydrocarbons is defluorinated similarly and is withdrawn as a product of the process.

Because the invention may be practiced in many ways other than as specifically described, and because many modifications will be apparent to anyone skilled in the art, the invention should not be restricted unduly by specific discussion presented herein.

I claim:

1. A process for the treatment of the hydrocarbon effluent from a hydrofluoric acid alkylation step in which isobutane is alkylated in the presence of normal butane, which comprises subjecting said hydrocarbon effluent to an azeotropic distillation whereby free hydrofluoric acid is removed; fractionating the hydrogen fluoride-free effluent so obtained to separate an isobutane fraction containing organic fluoride impurities, a normal butane fraction containing organic fluoride impurities, and a higher-boiling fraction also containing organic fluoride impurities; recycling said isobutane fraction to said alkylation step; passing said normal butane fraction to a first defluorination means containing aluminum oxide and maintained at a temperature in the range 150-300° F. and effecting therein a removal of fluorine from said fraction; subjecting the defluorinated material so obtained to dehydrogenation; separating from the effluent from said dehydrogenation a mixture comprising propene, butenes, and unreacted butane; passing said mixture to said alkylation step; passing said higher-boiling fraction to a second defluorination means containing aluminum oxide and maintained at a temperature in the range 150-500° F.; passing the substantially fluorine-free material so obtained to rerun means; and withdrawing from said rerun means a fraction boiling in the motor-fuel range and a fraction boiling above the motor-fuel range.

2. In a process for the alkylation of alkylatable organic compounds by reaction with a low-boiling olefin in the presence of a hydrofluoric acid catalyst, the improvement which comprises separating from effluents of such an alkylation a low-boiling paraffin hydrocarbon fraction containing as impurities a minor amount of organic fluorine compounds formed during said alkylation, subjecting said paraffin fraction to defluorination to produce a substantially fluorine-free paraffin fraction, dehydrogenating resulting fluorine-free paraffinic effluents of said defluorination to form low-boiling olefins, and passing low-boiling olefins so formed to said alkylation.

3. In a process for the alkylation of alkylatable organic compounds by reaction with a low-boiling olefin in the presence of accompanying low-boiling paraffin hydrocarbons and in the presence of a hydrofluoric acid catalyst, the improvement which comprises separating from effluents of such an alkylation a low-boiling paraffin hydrocarbon fraction containing as impurities a minor amount of organic fluorine compounds formed during said alkylation, subjecting said paraffin fraction to the action of a solid porous metal oxide catalytically active for hydrogenation and dehydrogenation reactions, at a reaction temperature and for a time such that extensive chemical changes in the paraffin hydrocarbons in said fraction are not effected and such that the total effluent from said treatment is es-

6

sentially fluorine-free, dehydrogenating resulting fluorine-free paraffinic effluents of said defluorination to form low-boiling olefins, and passing low-boiling olefins so formed to said alkylation.

4. In a process for the alkylation of alkylatable organic compounds by reaction with a low-boiling olefin in the presence of a hydrofluoric acid catalyst, the improvement which comprises separating from effluents of such an alkylation a low-boiling paraffin hydrocarbon fraction containing as impurities a minor amount of organic fluorine compounds formed during said alkylation, subjecting said paraffin fraction to the action of a solid porous metal oxide catalytically active for hydrogenation and dehydrogenation reactions, at a reaction temperature between about 150 and 550° F. and for a time such that extensive chemical changes in the paraffins in said fraction are not affected and such that the total effluent from said treatment is essentially fluorine-free, dehydrogenating resulting fluorine-free paraffinic effluents of said defluorination to form low-boiling olefins, and passing low-boiling olefins so formed to said alkylation.

5. The process of claim 4 wherein said porous metal oxide is alumina.

6. The process of claim 4 wherein said porous metal oxide is bauxite.

7. The process of claim 4 wherein said porous metal oxide is chromium oxide.

8. The process of claim 4 wherein said porous metal oxide is calcium oxide.

9. An improved process for reacting isobutane with normal butenes in the presence of a hydrofluoric acid alkylation catalyst, which comprises passing to an alkylation zone a butane mixture and normal butenes, maintaining the contents of said alkylation zone under alkylation conditions in the presence of a hydrofluoric acid alkylation catalyst to react said butenes with isobutane contained in said butane mixture, removing from effluents of said alkylation zone a hydrocarbon mixture free from free hydrofluoric acid, removing from said hydrocarbon mixture a fraction comprising unreacted isobutane and returning same to said alkylation zone, removing also from said hydrocarbon mixture a fraction comprising normal butane, said fraction being contaminated

50 with organic fluorine compounds, subjecting said normal butane fraction to the action of bauxite at a temperature between about 150 and 550° F. for a time such as to produce a substantially fluorine-free normal butane fraction, subjecting resulting fluorine-free normal butane to catalytic dehydrogenation to produce normal butenes, and passing normal butenes so produced to said alkylation zone.

10. An improved process for reacting isobutane with normal butenes in the presence of a hydrofluoric acid alkylation catalyst, which comprises passing to an alkylation zone a butane mixture and normal butenes, maintaining the contents of said alkylation zone under alkylation conditions

65 in the presence of a hydrofluoric acid alkylation catalyst to react said butenes with isobutane contained in said butane mixture, removing from effluents of said alkylation zone a hydrocarbon mixture free from free hydrofluoric acid, removing from said hydrocarbon mixture a fraction comprising unreacted isobutane and returning same to said alkylation zone, removing also from said hydrocarbon mixture a fraction comprising normal butane, said fraction being contaminated with organic fluorine compounds, subject-

ing said normal butane fraction to defluorination to produce a substantially fluorine-free normal butane fraction, subjecting the resulting fluorine-free fraction to dehydrogenation conditions to produce normal butenes, and passing said normal butenes so produced to said alkylation zone.

11. In a process for the alkylation of an isoparaffin having associated therewith a normal paraffin of three to five carbon atoms per molecule, in the presence of hydrofluoric acid as a catalyst, the steps comprising separating from the hydrocarbon effluent from the alkylation step a hydrogen fluoride-free fraction containing said normal paraffin together with a minor proportion of organic fluorine compounds, removing said fluorine compounds from said fraction, subjecting the fluorine-free fraction to dehydrogenation to convert normal paraffins contained therein to corresponding olefins, fractionating the effluent from said dehydrogenation step to separate a fraction comprising said olefins, and recycling said last-named fraction to said alkylation step.

12. The process of claim 11 wherein said normal paraffin is normal butane.

13. A process for the dehydrogenation of a low-boiling paraffin hydrocarbon material contaminated with a minor amount of fluorine in the form of organic fluorine compounds, which comprises subjecting such a hydrocarbon material to defluorination to produce a substantially fluorine-free paraffin hydrocarbon material, and subse-

5
8
quently subjecting the resulting fluorine-free paraffin hydrocarbon material to dehydrogenation.
